UNITED STATES PATENT OFFICE.

WILLIAM L. THOMAS, OF HIGDONS STORE, GEORGIA.

CULTIVATOR.

1,412,721.

Specification of Letters Patent. Patented Apr. 11, 1922.

Application filed April 13, 1917. Serial No. 161,803.

To all whom it may concern:

Be it known that I, WILLIAM L. THOMAS, a citizen of the United States, residing at Higdons Store, in the county of Fannin and 5 State of Georgia, have invented certain new and useful Improvements in Cultivators; and I do hereby declare the following to be a full, clear, and exact description of the invention, such as will enable others skilled in 10 the art to which it appertains to make and use the same.

This invention relates to cultivators, and the primary object of the invention is to provide a one-horse disc cultivator, which 15 includes a supporting frame, to which a pair of gangs of cultivating discs are attached, so that the disc may be adjusted with respect to the supporting frames for throwing the dirt inwardly toward each other and outwardly away from each other or the center 20 of the cultivator.

A further object of this invention is to pivotally connect the gangs of cultivating discs to the supporting frame and provide 25 hand levers, by means of which the angles of the discs, with respect to the direction of travel of the cultivator, may be varied as desired.

With the foregoing and other objects in 30 view, this invention consists in such novel features of construction, combination and arrangement of parts as will be hereinafter more fully described, illustrated in the accompanying drawings and claimed.

In describing the invention in detail reference will be had to the accompanying drawings wherein like characters designate like and corresponding parts throughout the several views, and in which:—

40 Figure 1 is a side elevation of the improved cultivator;

Figure 2 is a rear elevation of the cultivator;

Figure 3 is a top plan view showing the 45 discs positioned for throwing the dirt outwardly;

Figure 4 is a top plan view showing the discs positioned for throwing the dirt inwardly;

50 Figure 5 is a section on the line 5—5 of Figure 3; and

Figure 6 is a section on the line 6—6 of Figure 4.

Referring more particularly to the drawings, 1 designates the supporting frame of 55 the cultivator which is triangularly shaped,

having its side rails 2 and 3 converging at their forward ends. A clevis 4 is attached to the forward converged ends of the side rails 2 and 3 and it is provided for connection with a double or single-tree for hitching the draft animal to the cultivator. A longitudinally extending centrally disposed bracing bar 5 is carried by the frame 1 and it extends rearwardly from the forward converged ends of the side rails 2 and 3 and is connected to the rear cross bar 4 of the cultivator frame, as clearly shown in Figures 3 and 4 of the drawings. The rear cross bar 4 has a pair of forked members 5 60 pivotally connected thereto as shown at 6 through the medium of bolts 7. The forked members 5 comprise spaced arms 8 and 9. Suitable bearing or wear sleeves 11 are positioned about the bolts 7 as clearly shown 65 in Figure 5 of the drawings. The bolts 7, which extend through the bight portion of the substantially U-shaped or forked members 5 and through the rear cross bar 4, for pivotally connecting the forked members 5 70 to the rear end of the supporting frame so that the gangs of cultivating discs may be swung into the positions illustrated in Figures 3 and 4 of the drawings. These respective positions are provided for throwing 75 the dirt outwardly away from the center of the cultivator, or inwardly toward the center of the cultivator, as is desired in different cultivations.

The arms 8 and 9 extend downwardly 80 from the bar 4 and they are connected to the casings 14 which enclose or carry the disc bearings which are of the usual construction. Discs 15 which are carried by the casings 14 are of the ordinary construction employed in disc harrows or cultivators, having concaved portions and convexed portions as indicated in Figures 3 and 4 of the drawings, so that when the gangs are positioned as shown in Figure 4 85 of the drawings, the dirt loosened and broken up by the discs will be thrown inwardly or when the discs are positioned with their concaved portions positioned outwardly, they will throw the dirt outwardly 90 of the drawings, the dirt loosened and broken up by the discs will be thrown inwardly or when the discs are positioned with their concaved portions positioned outwardly, they will throw the dirt outwardly 95 away from the center of the cultivator.

One arm of each of the bracket members 5 has a hook 17 attached thereto, to which hook a bar 18 is connected. The bar 18 extends forwardly, and is adjustably connected, through the medium of a suitable bolt, as indicated at 19 to the lower end of 100

a hand lever 20. The hand lever 20 is pivotally carried by the center brace and it has a dog mechanism 21 carried thereby which coacts with a quadrant 22 carried by 5 the brace 5. Two of these levers are provided, one for connection to each of the bars 18, as will be seen by reference to the drawings, and pivotal movement of the levers will rock or move the forked members 10 5 upon their pivotal connection with the rear cross bar 4, so as to regulate the angle of the disc 15 with respect to the direction of travel of the cultivator.

The central brace 5 has handles 24 of 15 the usual construction attached thereto as indicated at 25 and these handles are connected intermediate their ends to upstanding angularly disposed braces 26. The braces 26 are attached to the rear cross bar 4 and 20 extend upwardly therefrom, having their upper ends converging and attached to the handles 24.

In reducing the invention to practice, such minor features of construction, combination and arrangement of parts may 25

necessitate alterations to which the patentee is entitled, provided such alterations are comprehended within the scope of what is claimed.

What is claimed is:—

An implement of the character specified, comprising a longitudinal bar having draft attaching means at its forward end, a cross bar attached centrally to the rear end of the longitudinal bar, brace bars at the sides 35 of the longitudinal bar and connecting the same with the cross bar, earth treating elements carried by said cross bar, handle bars connected to the opposite sides of said longitudinal bar, and inverted V-members 40 secured to opposite end portions of the rear cross bar and receiving the respective handle bars in their angles.

In testimony whereof I affix my signature in presence of two witnesses.

WILLIAM L. THOMAS.
